UNITED STATES PATENT OFFICE.

RICHARD A. COSTELLO, OF CHICAGO HEIGHTS, ILLINOIS.

BLACKBOARD-ERASER.

1,157,369.

Specification of Letters Patent. Patented Oct. 19, 1915.

Application filed December 26, 1914. Serial No. 879,036.

To all whom it may concern:

Be it known that I, RICHARD A. COSTELLO, a citizen of the United States, residing at the city of Chicago Heights, in the county 5 of Cook and State of Illinois, have invented certain new and useful Improvements in Blackboard-Erasers, of which the following is a specification.

My invention relates to the erasers which 10 are used for removing chalk marks from blackboards. Such erasers are best formed of strips of rubbing material so secured to an elastic or flexible back that a multiplicity of free ends are presented to form the rubbing faces. While this has been done in 15 many ways, my invention affords means of constructing an eraser which is light, resili- 20 ent and noiseless. My invention also pro- 25 vides means by which the parts may be firmly and securely fastened together, and the construction is particularly adapted to cheap and rapid manufacture.

The principles of my invention are illus- 25 trated in the drawings, in which—

Figure 1 shows a perspective view of a 30 complete eraser; Fig. 2 is a cross section thereof on the line 2—2 and shows a preferred form of construction; Fig. 3 is a similar section showing an alternative form 35 of construction; Fig. 4 is a cross section of one of the rubbing members.

Further describing my invention with refer- 35 ence to the drawings: 1 is a back piece, preferably of felt or similar material, which forms the foundation to which the rubbing 40 members are attached. The said rubbing members should be twice the width of the rubbing strips which are projected downwardly from the underside of the back or 45 foundation piece. Said members consist of pieces of suitable material, preferably felt, which should be longitudinally scored to form the cut faces 3 so that the two sections 4, forming the rubbing strips, may be turned 50 backward upon the uncut portion 5, whereby the sides 6 of the strips will be adjacent to each other. The said members each now forming two rubbing strips should be applied to the back piece 1, so that the cut and 55 squared faces 3 will be in contact with the underside of said back piece. When so placed rows of stitching 7 should be passed from a point 8 on the sides of the rubbing

strips, considerably removed from the back piece diagonally through the rubbing mem- 55 ber and the back piece. As the rubbing strips are somewhat inclined while the rows of stitching are being run, when placed in their proper position, practically at right angles to the eraser back, the rows of stitching 60 will be somewhat curved, as shown in the drawings.

The description as applied to Fig. 2 may also apply to the alternative form shown in Fig. 3, 7' representing the rows of stitching 65 by which the rubbing members are secured to the back, and 8' representing the points on the sides of the several rubbing strips at which the securing rows of stitching are applied. As a finish for the construction de- 70 scribed, a back piece 9 may be added and secured in place by a row of stitching 10.

It is found in practice that the method of construction shown, whereby two rubbing strips integrally formed are applied to the 75 back, provides a very desirable means by which the erasers may be made. The amount of stitching is much reduced, and while there are a comparatively small number of pieces to handle, the parts are more readily held in 80 proper relation while the operation of stitching them together is carried on.

Having thus fully described my invention what I claim as new and desire to secure by Letters Patent is—

In a blackboard eraser; the combination with a back piece of a plurality of rubbing members, said rubbing members being scored and turned backwardly at the score to form two attached rubbing strips with 90 continuous squared edges across the cut portion, which said edges are applied to the under side of the said back piece, and rows of stitching engaging the outer faces of said rubbing strips and passed upwardly and 95 diagonally therethrough and through the back.

In witness whereof, I have hereunto sub- 100 scribed my name, this 21st day of December 1914, in the presence of two subscribing wit- nesses.

RICHARD A. COSTELLO.
